[57] CLAIM

The ornamental design for pasta, as shown and described.

DESCRIPTION

FIG. 1 is a top plan view, in an enlarged scale, of the pasta of the present invention, the bottom plan view being a mirror image thereof;

FIG. 2 is a longitudinal cross-sectional view thereof, taken along line 2—2 in FIG. 1; and,

FIG. 3 is a top plan view thereof, at a greatly reduced scale.
